UNITED STATES PATENT OFFICE

WALTER HOWEY, OF NEW YORK, N. Y.

SOUND RECORDING ON FILM

Application filed July 1, 1930. Serial No. 465,191.

My invention relates to improvements in sound recording on films, and it more especially consists of the features pointed out in the claims.

The purpose of my invention is to provide a sound recording system that is of small bulk, of great ruggedness and sensitivity; that may be used in the studio or for portable sound recording simultaneously with the 10 photographing of the moving subjects; that because of its few moving parts and the steadiness and intensity of the light source makes it especially available for situations that at present are difficult to handle; and that may with equal facility use illumination 15 varying from ultra violet to infra red so as to coordinate the system for that portion of the spectrum to which the coating of the film may be specially sensitive.

With these and other ends in view, I illustrate in the accompanying drawing such instances of adaptation as will disclose the broad underlying features without limiting myself to the specific details shown thereon 25 and described herein.

Figure 1 is a diagrammatic view of the recording system.

Fig. 2 is a detached diagrammatic view of a quartz recorder.

In adapting my invention to the different uses of studio, station or special emergencies, I may utilize whatever alternatives or equivalents of structure and cooperating steps that the exigencies of varying conditions may demand without departing from the broad spirit of my invention.

In my recording system I make use of the unique characteristic of a quartz rod, or a quartz filament, or quartz filaments, or a cone shaped or tapering quartz rod so mounted as to convey light from any desired source through the quartz material and onto a sensitized receiving film as a diminutive point of light, the quartz element being suitably pivoted and acted upon by varying electric current so as to cause the end which is adjacent to the sensitized film to vibrate. The electric current for actuating the quartz element may be supplied by any desired system of sound pick up, amplification and modulation.

In Fig. 1 the sound receiving device may be an ordinary microphone suitably connected to a source of current (not shown) which under the varying vibrations of sound will impress such vibrations on an amplifying circuit. The current so amplified will cause the electromagnetic control to vibrate the small end of the quartz recorder in accord with the characteristic of the sound impressed on the receiving microphone so as to produce a sound track record on the movie film in motion adjacent the small end of the recorder. The oscillations of the point of light conveyed through the quartz element will produce lights and shades on the sensitive film of varying area to correspond with the frequencies and amplitudes of the impressed sound currents.

The quartz recorder shown diagrammatically in Fig. 2 may be pivoted at its large end to a hooded or enclosed source of light, and as stated, the small or pointed end of the conically shaped rod of fused quartz will be vibrated according to the characteristics of the vibrations to which the receiving microphone is subjected. This vibration may be effected electromagnetically in any desired manner.

A source of light 1 is enclosed in any desired form of hood 2 into which the conical end 10 of the quartz element 4 projects. The element 4 may be pivoted to the hood at 3. It is vibrated by an armature 6 which is set into vibration by any suitable electromagnet 7. The illumination from the source of light 1 engages the flattened end 11 of the quartz element 4. A movie film 5 is arranged in any well known manner to pass adjacent the small end 12 of the quartz element 4 so that a sound track will be formed on it adjacent to and simultaneous with the exposure of the usual movie film. In this way the vibrations impressed upon the receiving microphone 9 transmitted through the amplifying system 8 are recorded on the movie film.

I do not limit myself to any specific form of electromagnetic control of the quartz element as it may take on the characteristics of dynamic or other forms of loud speakers or the quartz element may be set into variable

vibration by any desired form of electrostatic control.

It is obvious that a quartz element at once provides a sound recording system that is 5 compact, simple, quite rugged and easily controlled so that it is especially adapted to studio or portable recording purposes.

What I claim is:

1. A sound recording system comprising a 10 source of light, a light sensitive medium, a tapered quartz filament adapted to collect light from the source and convey it to the light sensitive medium in the form of a point of light, and magnetic means for vibrating the quartz filament at a point adjacent the light sensitive medium in response to a suitable sound pickup and amplified output system.

2. In sound recording systems, in combination, a 20 traversing photo-sensitized film adapted to receive and record a sound track, a sound pickup, an amplifying system adapted to convert the sound vibrations into electrical vibrations, a source of light, a quartz rod, so mounted as to convey light from the source, and means for causing the electrical vibrations to control the movement of the quartz rod at a point adjacent the traversing film to produce an oscillographic recording 25 of the sound vibrations upon the film.

3. In sound recording, in combination, a 30 photo-sensitized material adapted to receive a sound track, means for moving the photo-sensitive material to provide for continuous recording of an oscillographic sound image, a fixed source of light, a sound pickup and amplifying system, a motor comprising an armature in the output of the amplifying system modulated by the output, a quartz rod 35 pivotally mounted with one end adjacent the source of light and the free end adjacent the photo-sensitive material, and means for causing the armature to actuate the free end to produce a light and shade recording of the 40 sound image upon the traversing photo-sensitized material.

4. In sound recording, in combination, a 45 source of light, a light sensitive medium, a quartz filament leading from the light source 50 to the moving photo-sensitized recording medium, and means for oscillating the free end of the quartz filament adjacent the light sensitive surface to produce a light and shade recording of light passing through the 55 quartz filament suitable for sound reproduction.

5. In sound recording, in combination, a 60 traversing photo-sensitized film adapted to receive a sound track, a source of light, 65 means for masking the light from the film, means for collecting part of the light and leading it through a plurality of quartz filaments to a corresponding number of points adjacent the photo-sensitive film, a sound pickup and amplifying system, and means

for vibrating the quartz filaments at the focusing points adjacent the traversing film so as to record a sound track responsive to the output of the sound pickup system.

6. In a system of the class described, a 70 source of light, a traversing light sensitive film, means for masking the light rays from the light sensitive film, a quartz filament, means for collecting part of the light rays and leading them through the quartz filament onto the light sensitive film, a sound pick-up, an amplifying system, and means for oscillating the quartz filament by the output of the amplifying system at the end adjacent the film so as to produce an oscillographic record of the sound on the film. 80

7. In a sound recording system of the class described, a source of light, a photo-sensitive material, a quartz filament interposed between the light source and the photo-sensitive material, means for causing the light passing through the quartz filament to be brought to a focus on the photo-sensitized surface, a suitable sound pickup comprising the input of an amplifying system, a magnetic motor which will vibrate in response to the output of the amplifying system and means for causing the vibrations of the magnetic motor to be transmitted to the quartz filament at the end adjacent the film, so as 90 to record on the film an oscillographic image of the sound. 95

In testimony whereof I affix my signature.
WALTER HOWEY.
